(57) **CLAIM**

The ornamental design for an apparatus for authenticating a user to receive wireless network services on a mobile communication device with biometric verification means, as shown and described.

DESCRIPTION

FIG. 1 is a top front perspective view of the apparatus for authenticating a user to receive wireless network services on a mobile communication device with biometric verification means, showing my new design;

FIG. 2 is a bottom perspective view thereof;

FIG. 3 is a front view thereof;

FIG. 4 is a rear view thereof;

FIG. 5 is a top plan view thereof;

FIG. 6 is a bottom plan view thereof;

FIG. 7 is a side view thereof; and,

FIG. 8 is a perspective view thereof in use.

The broken lines shown in the views are included for the purpose of illustrating portions of the apparatus for authenticating a user to receive wireless network services on a mobile communication device with biometric verification means that form no part of the claimed design.
